F. W. PICHT

CANNERY EXHAUSTER AND COOKER

Filed July 18. 1923

UNITED STATES PATENT OFFICE.

FREDERICK W. PICHT, OF SEATTLE, WASHINGTON, ASSIGNOR TO WRIGHT & SMITH MACHINE WORKS, A CORPORATION OF WASHINGTON.

CANNERY EXHAUSTER AND COOKER.

Application filed July 18, 1923. Serial No. 652,367.

To all whom it may concern:

Be it known that I, FREDERICK W. PICHT, a citizen of the United States, residing at Seattle, in the county of King and State 5 of Washington, have invented certain new and useful Improvements in Cannery Exhausters and Cookers; and I do hereby declare the following to be a full, clear, and exact description of the invention, such as 10 will enable others, skilled in the art to which it appertains, to make and use the same.

This invention relates to improvements in cannery exhaust boxes and more particularly to boxes which are adapted to contain 15 heated water through which the filled cans are adapted to be moved for the purpose of cooking the contents and for exhausting the air therefrom prior to the sealing of said cans.

20 An object of the invention is to provide a cannery exhaust box for holding a desired amount of hot water and positioning within said box a plurality of movable chains on which are adapted to be placed a plurality 25 of cans to be cooked and exhausted of air while passing through said water.

Another object of the invention is to provide a cannery exhaust box for holding hot 30 water and to position in the bottom of said box a plurality of movable chains, being movable in alternately opposite directions, and suitable rotating means at the ends of 35 said chains whereby cans of provisions placed on the said chains will be caused to travel the length of one chain and on to the next and on in like manner until the cans have traversed from the inlet to the outlet of said box.

A further object of the invention is to 40 provide an exhaust box for canneries, suitable means for carrying a plurality of cans of provisions down into said box and over a predetermined route and out of said box, during which time the contents of said cans 45 will be thoroughly cooked and exhausted of air after which they will be ready for sealing.

A still further object of the invention is 50 to provide a suitable construction of exhaust box for canneries, which will be provided with a series of steam pipes positioned along the bottom thereof to heat the water contained in said box to the desired temperature and to further provide said box with

a discharge gate for controlling the depth 55 of the water in said box.

Other objects will appear as the description proceeds.

In the accompanying drawings, which 60 form a part of my application,

Fig. 1 is a plan view of my improved ex- 65 haust and cooking box for canneries;

Fig. 2 is a longitudinal, sectional view 70 taken through one end and a portion of said box;

Fig. 3 is a detailed transverse sectional 75 view taken through a portion of and one side wall of the box showing a pair of conveyor chains and rotatable platform inter- positioned between the same, and

Fig. 4 is a detailed view partly in section 80 of a portion of one of the conveyor chains.

Like characters of reference are used 85 throughout the following specification and the accompanying drawings to designate 75 corresponding parts.

The exhausting and cooking box is pro- 90 vided with a bottom 1, sides 2 and ends 3, and is formed substantially rectangular in shape. The sides 2 of the box extend out 95 a considerable distance beyond the ends thereof and support rotatable shafts 4 and 5, which have fixed to one of their respective ends worm gears 6 and 7, which are positioned within suitable housings 8 and 9, 85 respectively, and mesh with worms 10 and 11, which are positioned at the opposite ends of the rod or shaft 12, which in turn is ro- 100 tatably supported in the brackets 13 at- tached to the outside of one of the sides 2 90 of the box.

A plurality of sprocket wheels 14 are positioned on the shafts 4 and 5 in such 105 a manner that alternate wheels are made fast to the said shafts by means of set screw or bolts 15, while the remaining wheels are rotatably mounted on the said shafts.

Suitable sprocket chains 16 extend be- 110 tween the shafts 4 and 5 in a manner that a fixed wheel on the shaft 4 will be connected with a loose wheel on the shaft 5 and vice versa. These sprocket chains 16 will, therefore, be so arranged and connected that the adjacent chains will move 105 in the opposite direction. The chains are passed under suitable small sprocket wheels 17 and 19 at the respective ends of the box

adjacent the bottom thereof, and are guided in suitable U-shaped channel members 18. The lower run of the chains pass under the said box as best illustrated in Fig. 2 of the drawings and then up over and into the box again.

Two rows of rotating platforms 20 mounted on suitable shafts 21 are positioned midway adjacent pairs of chains, one row at 10 either end of the box. The shafts 21 carry at their lower ends suitable beveled gears 22, which mesh with beveled gears 23 on transversely mounted shafts 24. These shafts 24 have positioned at their outer ends 15 suitable sprocket wheels 25, which are adapted to be connected with corresponding sprocket wheels 26 on shafts 4 and 5 by means of the sprocket chains 27.

Guard rails 28 are mounted longitudinally 20 of the box and between the sprocket chains 16 and serve to guide the cans of provisions 29 in their course of travel through said box. Suitable upwardly and inwardly extending tongues or deflectors 30 are mounted at the 25 opposite ends of the U-shaped channel members 18 and extend from the level of the chains to slightly above the level of the platforms 20, so that when the cans are conveyed toward said platforms they will be 30 lifted by said deflectors from the chains and on to the platforms where they will be carried to the next chain and deposited thereon.

A main sprocket wheel 31 on a shaft 35 35 is connected with a sprocket wheel 32 on the shaft 4 by means of a chain 33 and furnishes the necessary power for operating the several chains and rotating platforms. A sprocket wheel 34 is loosely mounted on the same shaft 35 and has a sprocket chain 36 40 connecting it with the last wheel 14 on the shaft 5 and which carries the cans up at an incline out of said box to a place where the said cans may be sealed.

A slideable closure member 37 is mounted 45 in a frame 38 at one side of the box and permits discharge of water from the box through the opening 39 in its side wall.

Steam pipes 40 are disposed in the box to keep the water at a high degree of temperature so that the contents of the cans 50 will be sufficiently heated to cook the same and exhaust the air therefrom.

In operation a suitable source of power (not shown) is connected with the shaft 35 which in turn rotates the several sprocket 55 wheels 14 causing the chains 16 to traverse the length of the box, the same being guided in U-shaped channel members. The cans 29 are placed on the chains at point 41 which is the entrance to said box, whereupon they 60 will pass or be carried by the chains to the opposite end of the box and on to one of the revolving platforms 20 there to be turned around and placed on the second sprocket chain. This performance is re- 65 peated until the cans finally pass out at the discharge end of the box on the chain 36.

It will be apparent and clearly understood that while I have shown and described my preferred form of exhausting and cook- 70 ing box for canneries, I do not intend to limit myself to the specific construction, detail and arrangement of parts, for many minor changes in detail of construction may be resorted to without departure from the 75 spirit of the invention.

Having thus described my invention what I claim is new and desire to secure by Letters Patent of the United States is:

In a cannery exhauster and cooker comprising a box adapted to receive and contain water, a plurality of alternately oppositely movable chains in said box, a plurality of rotating platforms at the ends of said chains, guide-tongues adjacent said platforms for elevating cans from said chains to said platforms, means for rotating said platforms for carrying said cans from a chain moving in one direction to a chain moving in an opposite direction, and a unitary means for operating and driving said chains and platforms. 80 85 90

In testimony whereof I affix my signature.

FREDERICK W. PICHT.
